LAMP

Charles R. Cassell, Oklahoma City, Okla.

Application February 27, 1953, Serial No. 23,826

Term of patent 14 years

(Cl. D48—20)

To all whom it may concern:

Be it known that I, Charles R. Cassell, a citizen of the United States, residing at Oklahoma City, in the county of Oklahoma and State of Oklahoma, have invented a new, original, and ornamental Design for a Lamp, of which the following is a specification, reference being had to the accompanying drawings, forming a part thereof:

In the drawings:

Figure 1 is a side elevational view of a lamp, showing my new design;

Figure 2 is a side elevational view of the lamp, looking from left to right of Figure 1;

Figure 3 is an enlarged horizontal sectional view of the lamp taken substantially along a plane as indicated by the line 3—3 of Figure 1;

Figure 4 is a horizontal sectional view on an

enlarged scale taken substantially along a plane as indicated by the line 4—4 of Figure 1, and

Figure 5 is an enlarged bottom plan view of the lamp base.

I claim:

The ornamental design for a lamp, substantially as shown.

CHARLES R. CASSELL.
